UNITED STATES PATENT OFFICE.

HUGH W. SANFORD, OF KNOXVILLE, TENNESSEE.

RAILWAY CAR.

Application filed January 20, 1922. Serial No. 530,629.

To all whom it may concern:

Be it known that I, HUGH W. SANFORD, a citizen of the United States, residing at Knoxville, in the county of Knox and 5 State of Tennessee, have invented a new and useful Improvement in Railway Cars, of which the following is a specification, reference being had to the accompanying drawing.

- 10 My improvement relates particularly to railway cars which are intended to dump their loads downward through the bottom of the car by the opening of hinged doors which form the bottom of the car. For a 15 car of this type, reference is made to my Letters Patent of the United States No. 1,268,390, granted June 4, 1918, for an improvement in railways. The object of the 20 present improvement is to provide for such a car a different form of latch mechanism to hold the rear door of the car in the closed position. In said Letters Patent, an important part of the latch mechanism is supported by the end wall of the car body; that 25 is to say, two angle levers are pivoted to the end wall of the car body, and each such lever has a downward-directed arm on which is a hook adapted to engage a tongue extending rearward from the rear edge of the rear 30 bottom door. It will be understood that the relation between the fulcri of said levers and said tongues should be constant (when the door is closed). But it has been found in practice that the end wall of the car does not 35 constitute as substantial a support for this part of the latch mechanism as can be had by using the adjacent end sill of the car for such support. If said end wall is made of lumber, there is tendency to warp out of 40 the original position, whereby the positions of the fulcri of said levers are changed. The same change may take place if the end wall of the car body is sheet metal; for such metal may become battered or bulged inward or outward. Furthermore, at times a 45 heavy impact against the end wall of the car body may force said end wall inward sufficiently to derange the positioning of said angle levers.
- 50 In my improved latch mechanism, the adjacent end sill is used as a support for the latch lever, only one lever being used, although it is to be understood that two such levers may be used if desired.

In the accompanying drawings, 55 Fig. 1 is an end elevation of a railway car embodying my improvement; Fig. 2 is an upright section on the line 2—2, of Fig. 1; Fig. 3 is a part of the same section drawn 60 to a larger scale; Fig. 4 is a detail end elevation, parts being broken away; Fig. 5 is a detail perspective, parts being omitted;

65 Fig. 6 is a perspective of the casting forming the downward-directed arm of the angle lever, said casting being laid into the horizontal position to show its rear face.

Referring to said drawings, A, A are 70 track rails. A¹, A¹ are ordinary car wheels supporting an axle, A². Said axle supports side sills, B, B, only one of which is shown; and the ends of the side sills support end sills, B¹, only one of which is shown. The 75 side sills and the end sills form the rectangular frame similar to that described in my Letters Patent mentioned above. On each side sill rests a side wall, C. At each end of the car an end wall, C¹, has its ends 80 joined to the ends of the side walls. Doors, D, D, form the bottom of the car. The rear door, D, the one at the right in Fig. 2, has its forward end hinged to the rear axle, A². In Fig. 2 said door is shown in the 85 closed or raised position, and it is to be held in said position until it is desired to dump the load. On the rear edge of said door is a wrist, D¹, which projects rearward approximately horizontally. From said wrist 90 a body, D², extends downward and forward against the lower face of the door and is secured to the door by means of rivets, D³, whereby said wrist is made rigid.

To the inner or forward face of the adjacent (the rear) end sill, B¹, is applied a compound standard, rising above said sill and composed of a straight member, E, and a bent member, E¹. The lower ends of said members overlap each other and are secured 100 to the end sills by rivets, E², extending through said two members and the adjacent upright wall of the end sill. The upper ends of the standard members, E and E¹, are separated sufficiently to receive between 105 them the angle lever comprising the horizontal arm, E³, and the shorter, downward-directed hook arm, E⁴, on which is the hook,

E^5 . The angle lever is supported on a journal, E^6 , extending horizontally through the members, E and E^1 , and said angle lever. The upper face of the hook, E^5 , is shown 5 slightly concave or downward curved, whereby the wrist, D^1 , will make such a seating on said hook as will require a slight lifting of said wrist to permit the hook to move sidewise from beneath said wrist.

10 Further tendency toward maintaining the engagement between the hook and said wrist is had through the downward pressure, by gravity, of the longer horizontal arm, E^3 , of the angle lever. A further addition to such tendency is had through the contracting coiled spring, E^7 , which has one end secured in the eye, E^8 , and has its other end secured in a bracket, E^9 , secured to the adjacent end wall brace, F . It is to 15 be understood that this spring may be omitted when the downward pressure of the horizontal arm, E^3 , is sufficient to make and maintain engagement between the hook, E^5 , and the wrist, D^1 .

20 In the form shown in the drawings, the arm, E^3 , and the downward-directed arm, E^4 , are separate pieces, the arm, E^3 , being a straight metal bar and the other arm being a casting having at its upper end a 25 horizontal channeled head, E^{10} , the channel of which receives the arm, E^3 . Bolts or rivets, E^{11} , extend through said head and the bar, E^3 , to secure said members immovably to each other.

30 The arm, E^3 , extends through a guide structure formed by the end wall brace, F , and the auxiliary piece, F^3 . The lower end of the brace is secured to the end sill by a bolt, F^1 , and the upper end of the brace is 35 secured to a horizontal metal strap, C^2 , on the outer face of the end wall, C^1 , by means of a bolt, F^2 . The auxiliary piece, F^3 , is secured to the brace, F , by means of bolts or rivets, F^4 . The arm, E^3 , extends between 40 the brace, F , and the auxiliary piece, F^3 .

45 The rear door, D , may be raised into the closed position by an attendant or automatically by such a track cam as is described in my Letters Patent above-mentioned. The door is to be released by lifting the outer or free end of the lever arm, E^3 . This may be done by the attendant when 50 the car has reached the place at which its load is to be dumped; or said arm may be lifted automatically by means of a relatively stationary member placed beside the track at the dumping station and adapted to engage the lower edge of the arm and push said arm upward during forward movement of the car on its arrival at the dumping station, as described in said Letters-Patent. It is to be understood that if 55 this automatic operation is desired, the arm, E^3 , is to be made long enough to reach horizontally outward beyond the side of the car

far enough to be engaged by such a relatively stationary member.

In addition to the advantage in avoiding the uncertainty of position of the fulcrum of the angle lever when said fulcrum is supported by the end wall of the car body, the present structure has the advantage of permitting the use of latch mechanism which is of the same form, although the side and end walls of the car body are varied. Furthermore, by applying the angle arm support to the end sill, the latch mechanism may be applied to a car before the side and end walls are put on the car. Then said walls may be applied by the purchaser in 70 the form best meeting his needs after he receives the car.

The several parts of the latch mechanism are preferably so proportioned as to avoid extending the hook, E^5 , below the end sill, 75 B^1 , and below the door, D , when the latter is closed. Thus the hook will be prevented from making contact with objects lying on the track when the car is moving either forward or backward.

90 I claim as my invention,

1. The combination with a car body comprising an end sill and a transversely hinged bottom door, of a wrist on said door, and latch mechanism supported by the end sill 95 and adapted to engage said wrist, substantially as described.

2. The combination with a car body comprising an end sill and a hinged bottom door, of a wrist on said door, a standard on 100 the end sill, and latch mechanism supported by said standard and adapted to engage said wrist, substantially as described.

3. The combination with a car body comprising an end sill and a hinged bottom door, 105 of a wrist on said door, and an angle lever supported by the end sill and having a hook adapted to engage said wrist, substantially as described.

4. The combination with a car body comprising an end sill and a hinged bottom door, of a wrist on said door, a standard on the end sill, and an angle lever supported by said standard and having a hook adapted to 110 engage said wrist, substantially as described.

5. The combination with a car body comprising an end sill and a hinged bottom door, of a wrist on said door, a standard supported on the end sill and comprising two members, and latch mechanism supported by said 115 standard and adapted to engage said wrist, substantially as described.

6. The combination with a car body comprising an end sill and a hinged bottom door, of a wrist on said door, an angle lever supported by the end sill and having a horizontal arm and a hook arm adapted to engage 120 said wrist, and a guide structure for said horizontal arm, substantially as described.

7. The combination with a car body com- 125

prising an end sill and a transversely hinged bottom door, of a wrist on said door, a latch mechanism comprising an angle lever having a horizontal arm and a hook arm adapted to engage said wrist, and an end wall brace joined to the end sill, and an auxiliary member forming a guide structure for said horizontal arm, substantially as described.

8. The combination with a car body comprising an end sill and a transversely hinged bottom door, of a wrist on said door and latch mechanism comprising an angle lever having a horizontal arm and a hook arm channeled to receive the horizontal arm, substantially as described.

9. The combination with a car body comprising an end sill and a transversely hinged door, of a wrist on said door, and latch mechanism comprising a spring and supported by the end sill and adapted to engage said wrist, substantially as described.

10. The combination with a car body comprising an end sill and a hinged bottom door, of a wrist on said door, a standard on the end sill, and latch mechanism comprising a spring and supported by said standard and adapted to engage said wrist, substantially as described.

11. The combination with a car body comprising an end sill and a hinged bottom door, of a wrist on said door, an angle lever supported by the end sill and having a hook adapted to engage said wrist, and a spring tending to hold said hook in engagement with said wrist, substantially as described.

12. The combination with a car body comprising an end sill and a hinged bottom door, of a wrist on said door, a standard on the end sill, an angle lever supported by said standard and having a hook adapted to engage said wrist, and a spring tending to hold said hook in engagement with said wrist, substantially as described.

13. The combination with a car body comprising an end sill and a hinged bottom door, of a wrist on said door, and latch mechanism applied to the inner face of the end

sill and adapted to engage said wrist, substantially as described.

14. The combination with a car body comprising an end sill and a hinged bottom door, of a wrist on said door, a standard applied to the inner face of the end sill, and latch mechanism supported by said standard and adapted to engage said wrist, substantially as described.

15. The combination with a car body comprising an end sill and a transversely hinged bottom door, of a wrist on said door, and latch mechanism supported by the end sill substantially above the lower face of said sill and adapted to engage said wrist, substantially as described.

16. The combination with a car body comprising an end sill and a transversely hinged bottom door, of a latch mechanism supported by the end sill and adapted to engage the door, substantially as described.

17. The combination with a car body comprising an end sill and a transversely hinged bottom door, of a standard on the end sill and latch mechanism supported by said standard and adapted to engage said door, substantially as described.

18. The combination with a car body comprising an end sill and a transversely hinged bottom door, of a latch mechanism supported by the end sill and adapted to engage the door and having an arm extending approximately parallel to the end sill, substantially as described.

19. The combination with a car body comprising an end sill and a hinged bottom door, of a standard on the end sill, and latch mechanism supported by said standard and adapted to engage the door and having an arm extending approximately parallel to the end sill, substantially as described.

In testimony whereof I have signed my name, this 6th (sixth) day of January, in 90 the year one thousand nine hundred and twenty-two.

HUGH W. SANFORD.
